ROBERT STRICKLER AND JOHN HENRY MCJANNETT, OF WOODSTOCK, ONTARIO,
CANADA.

RAILWAY GATE.

Application filed June 24, 1926. Serial No. 118,251.

This invention relates to a railway gate as described in the present specification and illustrated in the accompanying drawings which form part of the same.

5 The invention consists essentially of the novel features pointed out broadly and specifically in the claims for novelty following a description containing an explanation in detail of an acceptable form of the invention.

10 The number of accidents occurring at railway crossings is, as is well known, increasing constantly, the toll of human life and the material loss mounting every year. Various safety means, such as gates, signals, etc. are used with a varying amount of success. Signals warn the motorist, but he will quite often not heed it, believing that he can cross the railway track safely before the 15 approaching train has time to reach the crossing; it is common knowledge how this race between the automobile and the train often ends. Gates of the well known types are a more positive means of preventing the 20 motorist from taking a chance, but cannot be used extensively owing to the cost incurred in having a keeper to open it upon the approach of a train; and gates which are lowered and raised automatically are 25 not safe, accidents happening often owing to a gate lowering upon the car and therefore stalling it when partly across the track.

30 The objects of this invention, therefore, are to provide a very efficient and safe gate 35 which will serve as a barrier against reckless drivers, while eliminating the danger of an automobile becoming caught by a gate suddenly lowering upon it; to build a gate that will be automatic, reducing the cost 40 of its operation and therefore making the gate economically possible of use over an appreciable mileage of a railway; and generally to supply a reliable and dependable safety appliance capable of accomplishing 45 the aforesaid purposes.

In the drawings, Figure 1 is a diagrammatic plan view illustrating the operation of the gates.

50 Figure 2 is a diagram showing the system of wiring.

Figure 3 is an elevational front view of the device, showing the gate bar and the casing broken off.

Figure 4 is a bottom plan view of the clutch mechanism 23;

55 Figure 5 is a side elevation view of Figure 4.

Referring to the drawings, 10 designates 60 railway tracks, 11 the pavement of a highway or road crossing the tracks, 12 an automobile, and 13 the gates.

16 is a back plate mounting the mechanism operating the gate; it is suitably supported above the concrete base 15 by means of the posts 14. 16^A is a metal casing adapted to be secured upon the back plate 16, and having the door 16^B by means of which access is gained to the mechanism.

18 is a suitable motor suitably secured to the back plate and having the vertically arranged shaft 19. 20 is a shaft in vertical alignment with the shaft 19 and journaled in suitable bearings 21 and 22 which are secured to the back plate. 23 is a suitable clutch connecting the shaft 19 with the shaft 20, and it is so designed that 19 can rotate 70 20 whilst 20 cannot rotate 19. Figures 4 and 5 show the construction of this clutch.

56 is a round casing rigidly secured to the lower end of the shaft 20 by means of the cap screw 57. 58 is a flat metal bar having the hub 59 adapted to fit upon the upper end of the shaft 19, to which it is secured by means of the cap screw 60. 61 are two semi-circular bars hinged to the bar 58 at 62, rigidly carrying the weight 63 and pivotally carrying the friction fiber block 64. The free end of each of the bars 61 is provided with a spring 61^A attached to the other bar 61 at 65 and tensioned to normally hold the friction blocks 64 clear of the casing 56. As the shaft 19 is rotated, the bars 61 will be forced outwardly under the action of the weights 63 until the friction blocks engage the casing 56, causing the casing to rotate 85 with the shaft 19. 24 is a short shaft journaled in the bearing 22 and the bearing 25, and it is arranged in vertical alignment with the shaft 20. The shaft 20 rigidly carries a gear 27, and the shaft 24 rigidly car-

90 95 100

ries the gear 26. 30 is the gate bar having the hinges 31 which fit upon the shaft 24, and 29 are set screws or other suitable devices for adjustably securing the bar upon the shaft. The shaft 24 also rigidly carries the arm 33, and adjustable stops 34 and 34^A are provided in the path of the arm 33 for limiting the angular displacement of the gate bar.

35 is a long shaft rotating in bearings 36 and 37 secured to the back plate 16 and rigidly mounting the gear 38 which meshes with the gear 26; the shaft 35 also rigidly mounts the drum 40. 41 is a disc rigidly mounted upon the shaft 35 and carrying therewith a suitable friction pad 42. 43 is a gear loosely mounted upon the shaft 35 and meshing with the gear 27; the gear 43 is spring-held against the friction pad 42 by means of the compressed spring 44 which bears at its bottom end upon the cap 45 which is adjusted by turning the nut 46 on the threaded portion 47 of the shaft 35. 50 is a weight sliding on the rod 41 which is secured at its ends to suitable brackets fixed to the back plate 16. 43^A is a cable secured to the weight at one end and wound around the drum 40, the cable turning on the pulley 45 and the roller 46. 47 is a spring encircling the rod 41 for gradually destroying the momentum of the gate and the reciprocating parts of the mechanism before the arm 33 is swung to bear against the limiting stop.

35 The gate bar 30 is preferably balanced on each side of the hinge point by means of the counter weight 40^A, so as to reduce the bending moment of the shaft 24.

50^A is a battery suitably supported by the back plate and having a lead wire 51 connecting one of its terminals to one of the rails and having another wire 52 connecting its other terminal to one brush of the motor 18. 53 is a wire connecting the other brush of the motor to the other rail. 54 is a switch connected intermediate of the length of the wire 51 and enclosed in a suitable casing 54^A for breaking the circuit and therefore causing the gate to open, when a train for some reason or other, comes to a stop some distance before reaching the crossing and it is expedient to allow the traffic to proceed across the track. The wires 51 and 53 are connected to the rails at a distance away from the crossing sufficient to allow the usual time to elapse before the oncoming train reaches the crossing; and, following the usual practice, a section of the track is isolated so as to form a unit with the circuit.

60 Operation: As soon as the train has reached the section of the track which forms a unit with the circuit, the circuit will be closed and the motor started. The rotation of the shaft 19 will cause the rotation of

the gear 43 through the gear 27, and therefore rotate the shaft 35 and the drum 40. As the shaft 20 rotates, the shaft 24 will also be rotated owing to the engagement of the gear 26 with the gear 38, and therefore slowly cause the gate bar to swing until the lever 33 has reached the limiting stop 34^A. While the shaft 35 is rotated, the drum 40 will wind the cable and raise the weight 50. As soon as the train is past the highway, the circuit will be broken and the gate bar will swing back to its normal position under the weight of 50, the arm 33 now bearing upon the limiting stop 34. If in swinging, the motion of the gate is arrested by an obstruction, such as an automobile being partly upon the tracks, the gear 43 will slip upon the friction pad 42 and as soon as the obstruction is removed, the bar will again resume its swinging motion. As the clutch 23 is adapted to rotate the shaft 20 with the shaft 19 only when said shaft 19 is rotated, it follows that when the motor stops, the shaft 35 is free to rotate under the action of the weight 50, therefore causing the gate to automatically open.

What we claim is:

1. In a railway gate, a frame, a motor, a spindle, a bar carried by said spindle, a gear rigidly mounted upon said spindle, a long shaft arranged in parallel alignment with said spindle, a gear rigidly mounted upon said shaft and meshing with said first-mentioned gear, a friction disc rigidly secured upon said long shaft, a gear loosely mounted upon said long shaft and spring-held against said friction disc, a short shaft in alignment with said spindle and the motor shaft and lying therebetween, a clutch member interposed between the motor shaft and said short shaft adapted to operatively connect one with the other when the motor is rotating, a gear rigidly mounted upon said short shaft and meshing with said loosely mounted gear, and gravity operated means adapted for operating said short shaft in a direction opposite to that of the motor shaft.

2. In a railway gate, a frame, a motor and an electric circuit and battery, a vertically-arranged spindle, a horizontal bar carried by said spindle, a gear rigidly mounted upon said spindle, a long shaft arranged in parallel alignment with said spindle, a gear rigidly mounted on said shaft and meshing with said first-mentioned gear, a friction disc rigidly secured on said long shaft, a gear loosely mounted on said long shaft and spring-held against said friction disc, a short shaft in vertical alignment with said spindle and the motor shaft and lying therebetween, a clutch member interposed between the motor shaft and said short shaft adapted to operatively connect one to the other when the motor shaft is rotating, a gear

rigidly mounted on said short shaft and spindle, and adjustable means for limiting meshing with said loosely-mounted gear, a drum rigidly mounted on said long shaft, a weight slideable on vertically-arranged rods and a wire connected to said weight and wound around said drum, bearings secured to said frame for mounting said shafts and

Signed at Woodstock, Ontario, this 19th day of June, 1926.
